US0D1068646S

(12) **United States Design Patent** (10) **Patent No.:** **US D1,068,646 S**
(45) **Date of Patent:** **** Apr. 1, 2025**

(54) **CHARGING STATION**

(71) Applicant: **Volta Charging, LLC**, San Francisco, CA (US)

(72) Inventors: **Andrew Michael Riggs**, Oakland, CA (US); **Alexander Gustav Naasz**, Seal Beach, CA (US)

(73) Assignee: **Volta Charging, LLC**, San Francisco, CA (US)

(**) Term: **15 Years**

(21) Appl. No.: **29/868,088**

(22) Filed: **Nov. 18, 2022**

Related U.S. Application Data

(63) Continuation of application No. 29/772,666, filed on Mar. 3, 2021, now Pat. No. Des. 971,830.

CLAIM

The ornamental design for a charging station as shown and described.

DESCRIPTION

FIG. 1 is a front perspective view of a charging station showing our new design;

FIG. 2 is a right-side elevational view thereof;

FIG. 3 is a front elevational view thereof;

FIG. 4 is a left-side elevational view thereof;

FIG. 5 is a rear elevational view thereof;

FIG. 6 is a top plan view thereof; and,

FIG. 7 is a bottom plan view thereof.

The dash-dot-dash lines illustrate boundaries that form no part of the claimed design. The remaining broken lines depict portions of the charging station that form no part of the claimed design.

1 Claim, 7 Drawing Sheets
